UNITED STATES PATENT OFFICE.

JACKSON M. MARKHAM, OF WILLIAMSVILLE, MISSOURI.

CALF-WEANER.

SPECIFICATION forming part of Letters Patent No. 352,336, dated November 9, 1886.

Application filed September 22, 1886. Serial No. 214,253. (No model.)

To all whom it may concern:

Be it known that I, JACKSON M. MARKHAM, of Williamsville, in the county of Wayne and State of Missouri, have invented certain new and useful Improvements in Calf-Weaners; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to that class of devices known as "calf-weaners," and has for its object to furnish a device of this kind which will be simple in construction and effective in use for weaning calves and other young domestic animals.

It consists in the novel construction and arrangement of parts hereinafter fully described, and specifically designated in the claims.

Referring to the accompanying drawings, Figure 1 is a perspective view of a calf with my complete device properly arranged upon its head. Fig. 2 is a perspective view of the device detached. Fig. 3 is a sectional view taken on line $x-x$ of Fig. 2, showing the arrangement of the barbs. Fig. 4 is a detail top plan view of the adjustable nose-clamp. Fig. 5 is a section of the same, taken on line $y-y$ of Fig. 4. Fig. 6 is a perspective view of the nose-barb and its adjustable attaching-plate. Fig. 7 is a detail section taken on line $z-z$ of Fig. 2, showing the adjustable plate, its slot, and regulating-screw. Fig. 8 is a detail sectional view of one of the same, taken on line $z'-z'$ of Fig. 2; and Fig. 9 is a sectional detail view of one of the barbs with its spring-actuated shields, taken on line $y'-y'$, Fig. 3.

Like letters of reference mark the same parts in all the figures of the drawings.

Referring to the drawings by letters, A is the muzzle, having the neck-yoke B and the face-strap C.

D is the semicircular nose-bow, consisting of the curved sheet-metal plate c, the curved strap a, and the lip or curb strap b, the straps a and b being made of one continuous piece of leather, as shown in Fig. 3. The portion a, however, is given a set shape or form by the curved under strip or plate of metal c, riveted

to said strap a, as shown in section in Fig. 7, and the nose-bow being provided on each inner side with a barb, E.

Centrally on the strap a is secured the metal plate c', armed with a barb, E, and having the longitudinal slot d in its upper portion. This plate is attached or fastened between the leather a and the sheet metal c by a suitable screw, f, which is supported by a small bracket-plate, f', riveted to strap c, as shown in Fig. 8, said screw passing through plate f', the slot d, the strap c, and the clamping-nut g on the under side of the strap c, as shown in Figs. 7 and 8. the object of this construction allowing the plate c' to be longitudinally adjusted.

On the under side of the strap c, and in front or back of the nut g, is centrally arranged the leather or metal loop h, which acts as a hinge 70 or pivot for the snap-hook i, from which is suspended the adjustable nose-clamp F. This clamp F is designed to fit in the nostrils of the animal, thereby insuring the security of the muzzle. It consists of two curved arms, j K, 75 each provided with balls or tips j' k' at their outward or free ends, said arms being dovetailed or joined together in the following manner, viz: The arm K, at its inner end, is made rectangular in shape, and provided with a recess, n, having the inclined sides or walls, as shown. The inner end of the arm j is also rectangular in shape, and is formed with a central longitudinal slot, m, and slides easily in the recess n' of the arm K, as shown in Fig. 5. 80 The two arms j and K are secured together and rendered adjustable by the screw G, which passes through a small plate, l, fitting over the slot m of the arm j, and continuing through said slot takes its hold in the screw-threaded 85 hole n of the arm K. Thus it will be seen that when the screw G is loosened the clamping-plate l is released, and the arm j slides in the recess n', to bring the tips closer to or farther from each other, as described. 90

The barbs, as here shown, are three in number—viz., one on each side of the nose-bow and one on the forward end of the plate c'; but as many may be used as is found desirable. These barbs consist each of a cylindrical 95 socket, O, having the base-plate o' formed integral therewith, which forms a seat both for

the spur or barb B, centrally riveted in the base-plate o', and the coiled spring P. The shield Q is also of cylindrical shape, and fits easily within the socket O, and is provided 5 with an exterior flange, q, and an interior shoulder, r, which is designed to engage with a pin, s, which projects through one side of the socket O, the object of which construction is to prevent the normal tendency or pressure 10 of the spring from pressing the shield too far out of its socket, and the said shield is kept from being depressed too far by the circumferential flange q. This construction of barb I find most advisable to use; but I do not wish 15 to confine myself to the use of this before-described barb, nor to lay any claim thereto, since it forms part subject-matter of another application now pending in the United States Patent Office, filed September 18, 1886, Serial 20 No. 213,878, for cattle-pricker belts.

R is any suitable buckle or strap for securing the face-strap C to the nose-bow D, and S is a like fastening for the ends of the curb-strap b and nose-strap a.

25 The neck-yoke B is riveted to the face-strap C, and attached at its lower end to the lip or curb strap, as shown in Fig. 2.

The operation of my invention may be briefly described as follows: The muzzle is arranged 30 on the head of the calf, as shown in Fig. 1, with the tips of the nose-clamp in the nostrils and the nose-bow and barbs in position. Should the calf then attempt to feed from its mother it would necessarily have to poke its nose forward and against the udder, which would depress the flexible plate o', carrying the barb E 35 against its nose. Consequently the spring-actuated shield of the barb would be depressed, thereby exposing the spur or barb-rod and 40 prod the nose of the calf. The barbs on the inner sides of the nose-bow will operate in like manner should the calf endeavor to escape the central barb by moving its nose to one side thereof.

45 It will be obvious that by making the sev-

eral parts of the device adjustable the device can be arranged upon any-sized calf or other animal where my invention would be of service.

Having thus fully described my invention, what I claim, and desire to secure by Letters 50 Patent of the United States, is—

1. A calf-weaner consisting of a muzzle provided with a nose-bow having inner side barbs, the curved adjustable central front plate having a barb on its inner front end, and the 55 adjustable nose-clamp suspended from said nose-bow, as set forth.

2. The muzzle provided with the semicircular nose-bow armed with barbs on its inner side, and the curved adjustable central front plate 60 having barbs, said barbs being provided with spring-actuated shields, in combination with the adjustable nose-clamp, as set forth.

3. A calf-weaner consisting of the yoke, the face-strap, lip or curb strap, the nose-bow provided with barbs on its inner side, the adjustable curved central front plate, also provided with a barb, and means for attaching said parts together, as described, in combination with an adjustable nose-clamp suspended from 70 said nose-bow, in the manner described.

4. The nose-clamp consisting of two curved arms having a tip at each of their outer ends and adjustably secured together in the middle, in the manner shown, in combination with a 75 nose-bow having barbs arranged on its inner side and the curved adjustable central front plate, also provided with barbs, as set forth.

5. In a calf-weaner, the combination of the adjustable nose-clamp with a muzzle having 80 a nose-bow provided with barbs on its inner side, arranged as described.

In testimony that I claim the foregoing as my own I affix my signature in presence of two witnesses.

JACKSON M. MARKHAM.
